WAGON

Walter B. Schumacher and Albert M. Best, New Holland,
Pa., assignors to Sperry Rand Corporation, New Hol-
land, Pa., a corporation of Delaware

Application February 11, 1958, Serial No. 49,602

Term of patent 14 years

(Cl. D14—3)

Fig. 1 is a front perspective view of a wagon embodying our new design, and

Fig. 2 is a fragmentary detail view of a portion of the body paneling.

The rear of the wagon is the same as the front. The side of the wagon not illustrated is the same as the side shown. The top of the wagon is open and the floor of the wagon is plain.

We claim:

The ornamental design for a wagon, as shown and described.
